BABY BATH

Dora J. Seivert, 1712 Edgewater Blvd.,
Minneapolis, Minn.
Filed Nov. 23, 1960, Ser. No. 71,336
2 Claims. (Cl. 4-177)

This invention relates to bathtubs and more particularly to a collapsible bathtub for infants.

An important object of this invention is to provide a simple and inexpensive infant's bathtub which is readily collapsible to a small and flat configuration which renders it convenient for handling and storage.

Another important object of this invention is to provide a combination which includes two tubs, one a conventional bathtub and the other an interfitting cooperatively disposed bathtub, the latter utilizing the faucet and drainage facilities of the conventional tub.

A further object of this invention is to provide an infant's bathtub which has a simple and efficient means for keeping the infant's eyes and nose clear of the soap suds and water.

A still further object of this invention is to provide a bathtub as described above which may be easily cleaned and dried after use.

These and other objects and advantages of my invention will more fully appear from the following description, made in connection with the accompanying drawing wherein like reference characters refer to the same or similar parts or designations throughout the several views and in which:

FIGURE 1 is an elevational side view of the infant's bathtub;

FIGURE 2 is an end view of FIGURE 1; and

FIGURE 3 is a cross-sectional view of FIGURE 1 taken at cross section 3-3.

FIGURE 4 shows a side view of a conventional bathtub with a portion thereof broken away to show the invention included therein. Elements not necessary to the full understanding of this invention have been removed beyond the outermost broken line.

Referring again to FIGURE 1, the infant's bathtub 10, shown in the open position, is comprised of four main elements: two U-frame members 11 and 12, a collapsible tub 13 suspended from the two U-frame members 11 and 12, and a head support strap 14 also supported by U-frame members 11 and 12 and attached to the tub 13 along the side 15.

Located at either end of the bathtub structure are fastening means 16 which pivotally secure the two U-frame members 11 and 12 together. Located adjacent and above the fastening means are folding braces 17 which add structural support to the bathtub when the tub 13 is in the open position. The folding braces 17 may be collapsed when the tub is made ready for storage as may be further understood by referring to FIGURE 2.

Located on the lower end of the two U-frame members are protective covers 18 which prevent any scratching or marring by the U-frame member of the surface on which the bathtub is situated.

Referring now to FIGURE 3, the head support strap 14, one of the important features of this invention, may be seen in cross-sectional view showing its spaced relation above the bottom of the tub. As may be seen in FIGURE 3, the head support strap is secured adjacent the U-frame members to sides 15 of the tub and may be so angulated that edge 14a of the head strap is somewhat closer to the bottom of the tub 13 than is edge 14b for a reason to be explained subsequently. The head support strap 14 is sewn to the sides 15 along seam 19 at the same time that the overlying portion of the tub is

2

sewn, thereby providing a simple single operation construction.

FIGURE 4 illustrates a combination showing a conventional bathtub 20 with my baby bathtub 10 included therein. The ends 21 and 22 of the conventional bathtub 20 abut walls 23 and 24 respectively and side 25 lies adjacent wall 26. A portion of the conventional tub side 27 has been broken away thereby showing the relative positions of the faucet 28, the conventional bathtub drain 29 and the intermediate position of the baby bathtub with one end thereof underlying the faucet 28.

In use, my infant's bathtub would be removed from its storage place and opened until the folding braces 17 are extended and in locked position. Then the infant's bathtub may be placed in a conventional bathtub and one end thereof located below the conventional bathtub's water faucet. Once filled with water of the desired amount and temperature, the baby may be laid in the bathtub 10 with its head resting on the head support strap 14 located at one end of the tub 13.

It will be explained at this point that the head strap 14 may be conveniently secured to the sides of tub 13, adjacent the juncture with the U-frame member, at such an angle that the edge 14b is somewhat raised from the level of edge 14a. The purpose of this particular type of construction is to provide a sloping support of the baby's head thereby avoiding an abrupt edge which may cause the baby discomfort when lying on his back. In this manner, the baby's head will lie substantially in a smooth and gradually inclining curve with the rest of his body when he is positioned with his body lying on the bottom of the tub in the wash water and his head on the head rest. By means of head strap 14, the baby's head will be so positioned at all times as to prevent the baby's face from becoming submerged in the water.

After the baby has been bathed, it is a very simple procedure to lift up on one end of the infant's bathtub 10 and thereby spill the water over the other end of the tub 13 allowing it to fall within the conventional bathtub. Thereupon, the water is allowed to freely discharge through the conventional bathtub drain. Since the infant's bathtub is made of a flexible sheet material, it may readily be seen that a dry sponge is all that is needed for quick and easy drying and cleaning of the tub portion. Once the tub has been dried, the infant's bathtub may be collapsed by disengaging the folding braces on either end thereof and bringing the two sides of the tub together.

It will, of course, be understood that various changes may be made in the form, details, arrangement and proportions of the parts without departing from the scope of my invention as set forth in the appended claims.

What is claimed is:

1. A baby bath comprising, a pair of inverted U-frames each having downwardly extending leg members pivotally secured together in crossed relation, said U-frames having respective spaced parallel and horizontal portions intermediate said downwardly extending leg members, a folding brace pivotally secured to opposing U-frame leg members adjacent their pivotal securing, a flexible sheet having a medial cavity suspended at the sides thereof between said parallel and horizontal portions of said U-frames, and an elongated flexible strap secured endwise to the sides near said horizontal portions of said U-frames and adjacent one end of said flexible sheet, said flexible strap lying in spaced relation above the medial cavity of said flexible sheet.

2. A baby bath comprising, a pair of inverted U-frames each having downwardly extending leg members pivotally secured together in crossed relation, said U-frames having respective spaced parallel and horizontal portions intermediate said downwardly extending leg

members, a flexible sheet having the marginal sides thereof of encircling said parallel and horizontal portions of said U-frames, an elongated flexible strap adjacent one end of said flexible sheet having a length less than the width of said sheet, a seam at each side of said sheet passing through said encircling marginal sides of said sheet and the ends of said strap, and means connected to said U-frame leg members for limiting the angularity of said U-frame leg members, whereby said flexible sheet is suspended with a medial cavity therein and said flexible strap lies in a spaced relation above said medial cavity when

10 said U-frame leg members are at an angle determined by said limiting means.
